(57) **CLAIM**

We claim the ornamental design for a beverage dispenser, as shown and described.

DESCRIPTION

FIG. 1 is a top perspective view of a beverage dispenser showing the new design;

FIG. 2 is a bottom perspective view thereof;

FIG. 3 is a right side view thereof, the left side view being a mirror image;

FIG. 4 is a front end view thereof;

FIG. 5 is a rear end view thereof;

FIG. 6 is a top view thereof; and,

FIG. 7 is a bottom view thereof.

The broken lines in the figures depict portions of the beverage dispenser that form no part of the claimed design.

1 Claim, 4 Drawing Sheets
